UNITED STATES PATENT OFFICE.

RUFUS N. PRATT, OF HARTFORD, CONNECTICUT, ASSIGNOR TO THE PRATT & CADY COMPANY, OF SAME PLACE.

STEAM-VALVE.

SPECIFICATION forming part of Letters Patent No. 291,770, dated January 8, 1884.

Application filed March 27, 1883. (No model.)

To all whom it may concern:

Be it known that I, RUFUS N. PRATT, of Hartford, in the county of Hartford and State of Connecticut, have invented certain new and useful Improvements in Steam-Valves; and I do hereby declare that the following is a full, clear, and exact description thereof, whereby a person skilled in the art can make and use the same, reference being had to the accompanying drawings, and to the letters of reference marked thereon.

Like letters in the figures indicate the same parts.

Figure 1 is a view in central section of my improvement as embodied in a straight-way valve. Fig. 2 is a view in central section of same in an angle-valve.

My invention relates to the class of fluid-valves in which a swinging flap is used; and it consists in the peculiar and special combination and arrangement of parts, by which I secure in one body a check and stop valve combined.

In the accompanying drawings, the letter *a* denotes a valve-body as a whole; *b*, a valve-seat; *c*, a flap-valve pivoted to the body in such position as to open and close the way *b* in swinging; *d*, a screw-cap and stuffing-box of usual form, adapted to be secured to body *a*, and bearing screw-spindle *e*, by means of which the flap *c* may be firmly held to its seat, or by which its play may be limited to any desired extent within the extremes of its swing or play. On the

back of the flap a rib or stop, *c'*, is formed, so curved as to present a bearing to the foot of 35 the spindle, under its center and substantially in the line of its axis, in all parts of the path of the flap in swinging. By screwing down the spindle, as shown in Fig. 1, the valve is securely closed and forms a stop-valve; but 40 by raising the spindle, as shown in Fig. 2 and in dotted lines in Fig. 1, a check-valve is formed.

In my improved valve-body any form of valve disk or packing may be used, although 45 the drawings show the flap and rotary disk common to special forms.

I claim as my invention—

1. In a check and stop valve, in combination, body *a*, having valve-seat *b*, swinging flap *c*, having stop *c'*, with the curved surface, and the screw-spindle *e*, the said curved surface forming a bearing for the foot of the screw-spindle *e*, whereby the play of the flap is limited, all substantially as described. 55

2. In a check and stop valve, in combination, the screw-spindle and the swinging flap, bearing a curved stop, the surface of which at all points in the path of the flap in swinging bears on the spindle in line of its axis, all substantially as described. 60

RUFUS N. PRATT.
